US0D1079379S

(12) **United States Design Patent** (10) Patent No.: **US D1,079,379 S**
(45) Date of Patent: ** Jun. 17, 2025

(54) **REMOVABLE PART FOR AN APPARATUS FOR THE PREPARATION OF FOOD AND DRINK**

(71) Applicant: **Vorwerk & Co. Interholding GmbH**, Wuppertal (DE)

(72) Inventor: **Felix Thies**, Wuppertal (DE)

(73) Assignee: **Vorwerk & Co. Interholding GmbH**, Wuppertal (DE)

(**) Term: **15 Years**

(21) Appl. No.: **29/880,394**

(22) Filed: **Jul. 21, 2023**

Related U.S. Application Data

(62) Division of application No. 29/808,245, filed on Sep. 17, 2021, now Pat. No. Des. 1,031,360.

(57) **CLAIM**

The ornamental design for removable part for an apparatus for the preparation of food and drink as shown and described.

DESCRIPTION

FIG. 1 is a top, right perspective view of a removable part for an apparatus for the preparation of food and drink showing my new design;

FIG. 2 is a bottom, left perspective view thereof;

FIG. 3 is a right side view thereof;

FIG. 4 is a front view thereof;

FIG. 5 is a left side view thereof;

FIG. 6 is a rear view thereof;

FIG. 7 is a top view thereof; and,

FIG. 8 is a bottom view thereof.
